Primary Examiner — Dana L Meyrow*(74) Attorney, Agent, or Firm* — Norton Rose Fulbright US LLP(57) **CLAIM**

The ornamental design for a cosmetic bottle, as shown and described.

DESCRIPTION

FIG. 1 is a top perspective view of our bottle; FIG. 2 is a front view of the bottle shown in FIG. 1; FIG. 3 is a back view of the bottle shown in FIG. 1; FIG. 4 is a right side view of the bottle shown in FIG. 1; FIG. 5 is a left side view of the bottle shown in FIG. 1; FIG. 6 is a top view of the bottle shown in FIG. 1; and, FIG. 7 is a bottom view of the bottle shown in FIG. 1. The broken lines in the drawings illustrate the portions of the cosmetic bottle that form no part of the claim.
